SUCTION CLEANER NOZZLE

Carl Eric Sixten Andersson-Sason, Solna, Sweden, assignor
to Aktiebolaget Elektrolux, Stockholm, Sweden, a cor-
poration of Sweden

Application March 21, 1956, Serial No. 40,698

Claims priority, application Australia September 23, 1955

Term of patent 14 years

(Cl. D9—2)

Fig. 1 is a front perspective view of a suction cleaner nozzle showing my design;

Fig. 2 is a rear perspective view with the nozzle in the position shown in Fig. 1;

Fig. 3 is a side view with the nozzle in the position shown in Fig. 1;

Fig. 4 is a top plan view with the nozzle in the position shown in Fig. 1; and

Fig. 5 is a bottom plan view with the nozzle inverted from the position shown in Fig. 4.

What I claim is:

The ornamental design for a suction cleaner nozzle, as shown.
